PAPER RECEPTACLE

Charles O. Ball, Maumee, Ohio, assignor to
 Owens-Illinois Glass Company, a corporation
 of Ohio

Application May 19, 1945, Serial No. 594,696

5 Claims. (Cl. 229—38)

1

My invention relates to articles made from blanks of paper or other sheet material adapted to be folded along fold lines or score lines of predetermined pattern formed in the blanks, for shaping the article. The invention provides an article having a rectangular body with a closed end and, in the form herein illustrated, may be used as a container for milk or other liquids.

An object of the invention is to provide an improved form of receptacle having a rectangular body and a bottom end folded from a single sheet of material designed to provide a bottom which is practically invulnerable to leakage. For this purpose the bottom end of the receptacle is designed to avoid a thickness of more than three layers or plies of the folded material.

A further object of the invention is to provide a blank giving efficient use of the material, permitting the blanks to be cut from the strip of stock with very little waste of the material.

A still further object of the invention is to provide a novel container of the character indicated in which there are no joints in the bottom corners and no cut edges extending to any of the corners.

Other objects of the invention will appear hereinafter.

Referring to the accompanying drawings:

Fig. 1 is a plan view of a flat blank of sheet material cut and scored for folding to form a rectangular receptacle embodying my invention.

Fig. 2 is a perspective view on a larger scale, of the receptacle in an inverted position, the bottom end being shown partly folded.

Fig. 3 is a horizontal cross section of the receptacle giving a plan view of the inner surface of the folded bottom.

Fig. 4 is a fragmentary view of a detail showing a modified construction.

Referring to Fig. 1, the blank is cut from a strip of paper or other sheet material and is provided with fold lines, indicated on the drawing by broken lines, along which the blank is folded for shaping the article. The fold lines may consist of score lines, creases, or weakened lines. The blank is adapted to be folded along parallel fold lines 4, 5, 6, and 7, to form the rectangular body of the receptacle, said body comprising panels or sides 8, 9, 10 and 11. The upper and lower margins of the body are defined by score lines 12 and 13 respectively. A side seam strip 14 is adapted to be folded inwardly along the line 1 and forms a flap to lie against the inner surface of the panel 8 to which it is attached by adhesive material to form a liquid-tight seam.

2

The panels 8, 9, 10, and 11 have bottom-forming extensions or sections 15, 16, 17, and 18, foldable inwardly along the score line 13 after the body has been formed, to shape the bottom of the container. These extensions are not separated by lines of cleavage, the adjoining edges of the extensions being united along the fold lines 4, 5 and 6 which are extended downward through the bottom-forming portion of the blank.

10 The outline of the bottom-forming portion of the blank is defined by lines extending between the points V, W, A, B, C, D, E, F, G, H, I, L, M, and Q. The score line 13 intersects the corner score lines 4, 5, 6, and 7 respectively, at the points R, S, T, and U. The extension 16 is divided into a major section 16' and triangular sections 16^a and 16^b by diagonal score lines SI, JR and slits JK, KL, the latter being an extension of the score line 4. The rectangular extension of the section 16', bounded by lines JKLI, may be removed if desired by severing along an extension of the score line RJ. The end extension 18 is also divided into a major section 18' and triangular sections 18^a and 18^b by means of diagonal score lines TD and CU.

20 The side seam strip 14 is extended downward below the marginal line 13, providing an extension 14^a having an outer edge VW inclined diagonally downward and outward below the fold line 30 13. The extension 14^a is thus formed with a triangular enlargement having a diagonal side VW and a horizontal base in the line WA. The width of the extensions 15, 16, and 18 as shown, is half the width of the narrow panels 9 and 11. The 35 section 17 is extended to a greater width, the extended portion being defined by the lines EF, FG and GH.

40 The blank is folded to form the receptacle by first folding along the lines 4, 5, 6, and 7 to form the rectangular receptacle body, the seam strip 14 being then adhered to the inner face of the panel 8. With the blank thus folded, the extension 14^a of the seam strip 14 overlaps the end section 15, the diagonal edges VW and QM being 45 parallel. The seam is thus carried into the bottom-forming portion of the blank and extends entirely across the section 15.

50 The bottom-forming portion of the blank, comprising the sections 15, 16, 17 and 18, is then folded inwardly to form the bottom. The sections 16 and 18 when folded inwardly to horizontal position form a portion of the inner surface of the bottom as seen in Fig. 3. As the section 18 folds inwardly the triangular sections 18^a and 18^b 55 are simultaneously folded back over the section

18' and form an intermediate layer of the container bottom. The section 15 as it is folded inwardly is brought over the section 18', so that the extension 14^a of the seam strip, except that portion thereof which is overlapped by and adhered to the section 15, overlies the section 18'. The triangular section 18^b is thus interposed between the sections 18' and 14^a. The section 17 folds over the section 15 and thereby forms the outermost layer of said bottom, the major portion of the bottom surface being formed by the section 17, and the remaining portion by the section 15, except a small triangular corner where the section 15 is cut away and exposes a portion of the underlying section 18'. The section 16 folds inwardly in substantially the same manner as above described in connection with the section 18, the section 16^a being folded in between the section 18' and the section 17. The triangular section 16^b is folded in to lie between the section 18' and the section 15. The section 16' which forms a part of the innermost layer of the receptacle bottom is of generally triangular form with a rectangular extension defined by the lines JK, KL and LI. When the fold lines 4, 5, 6, and 7 are equally spaced or approximately equally spaced to form a substantially square receptacle body, the modified form of side seam extension shown in Fig. 4 may be used. This extension 14^b differs from the extension 14^a (Fig. 1) by having the outer triangular corner removed along a line b parallel with the line AB, thereby shortening the diagonally outwardly inclined edge so that the line b passes through the apex of the triangle 18' (Fig. 3) when the blank is folded. This prevents the side seam extension being carried beyond the center of the folded bottom and thus prevents a four-ply thickness.

In the folded bottom, butt joints are formed as follows:

The sections 14^a and 18^a form a butt joint at their meeting edges AW and ED. The edge LM of the section 15 makes a butt joint with the edge HI of the section 16^a. A butt joint offset by the thickness of the interposed section 14^a, is formed by the edge BC of triangle 18^b and the edge FG of the section 17. A butt joint, offset by the interposed section 15, is likewise formed by the edge JK of the section 16^b and the edge FG of the section 17.

The juxtaposed parts or layers of the folded blank are secured in position in any approved manner by an adhesive or bonding material.

Modifications may be resorted to within the spirit and scope of my invention.

I claim:

1. A flat blank of foldable sheet material shaped and provided with weakened fold lines adapting it to be folded to form a receptacle having a rectangular body and a closed bottom end, said blank having parallel fold lines defining four panels which form the body of the receptacle, each two alternate panels being of equal width, the blank including a body seam strip in addition to said panels and extending along one edge of the blank between said edge and a said fold line, said blank having a bottom margin fold line extending throughout the length of the blank in a direction perpendicular to said parallel lines and separating the body-forming portion of the blank from a bottom-forming strip, said parallel lines extending through said bottom-forming portion and dividing it into sections individual to the panels and foldable inwardly along said bottom line for forming the bottom, said seam strip being extended through said bottom-forming portion and having an outer edge inclined diagonally downward and outward below said bottom fold line, providing an extension positioned and arranged to overlap the opposite end of the bottom-forming portion of the blank when the blank is folded, the end edges of said bottom-forming strip being parallel, whereby the body seam is carried into said bottom at one corner thereof and across a portion of said bottom in a diagonal direction.

2. A blank of foldable sheet material shaped and provided with weakened fold lines adapting it to be folded to form a receptacle having a rectangular body and a closed bottom end, said blank having parallel fold lines defining the panels which form the body of the receptacle, the blank including a body seam strip extending along one edge of the blank between said edge and a said fold line, said blank having a bottom margin fold line extending throughout the length of the blank in a direction perpendicular to said parallel lines and separating the body-forming portion of the blank from a bottom-forming strip, said parallel lines extending through said bottom-forming portion and dividing it into sections individual to the panels and foldable inwardly along said bottom line for forming the bottom, said seam strip being extended through said bottom-forming portion and having an outer edge inclined diagonally downward and outward below said bottom fold line, providing an extension positioned and arranged to overlap the opposite end of the bottom-forming portion of the blank when the blank is folded, thereby carrying the body seam into and across a portion of said bottom in a diagonal direction.

3. A blank of foldable sheet material shaped and provided with weakened fold lines adapting it to be folded to form a receptacle having a rectangular body and a closed bottom end, said blank having parallel fold lines defining the panels which form the body of the receptacle, the blank including a body seam strip extending along one edge of the blank between said edge and a said fold line, said blank having a bottom margin fold line extending throughout the length of the blank in a direction perpendicular to said parallel lines and separating the body-forming portion of the blank from a bottom-forming strip, said parallel lines extending through said bottom-forming portion and dividing it into sections individual to the panels and foldable inwardly along said bottom line for forming the bottom, said seam strip being extended through said bottom-forming portion and having an outer edge inclined diagonally downward and outward below said bottom fold line, providing an extension positioned and arranged to overlap the opposite end of the bottom-forming portion of the blank when the blank is folded, thereby carrying the body seam into and across a portion of said bottom in a diagonal direction, said parallel fold lines being spaced to provide comparatively narrow panels alternating with wider panels, the said bottom-forming strip having a triangular corner portion thereof cut away at the end of the strip opposite said side seam strip extension whereby the sides of the seam portion which is carried into the said bottom are substantially parallel.

4. A blank of foldable sheet material shaped and provided with weakened fold lines adapting it to be folded to form a receptacle having a rectangular body and a closed bottom end, said blank having parallel fold lines defining the panels which form the body of the receptacle, the blank including a body seam strip extending along one edge of the blank between said edge and a said fold line, said blank having a bottom margin fold line extending throughout the length of the blank in a direction perpendicular to said parallel lines and separating the body-forming portion of the blank from a bottom-forming strip, said parallel lines extending through said bottom-forming portion and dividing it into sections individual to the panels and foldable inwardly along said bottom line for forming the bottom, said seam strip being extended through said bottom-forming portion and having an outer edge inclined diagonally downward and outward below said bottom fold line, providing an extension positioned and arranged to overlap the opposite end of the bottom-forming portion of the blank when the blank is folded, thereby carrying the body seam into and across a portion of said bottom in a diagonal direction, said parallel fold lines being spaced to provide comparatively narrow panels alternating with wider panels, the said bottom-forming strip having a triangular corner portion thereof cut away at the end of the strip opposite

said side seam strip extension whereby the sides of the seam portion which is carried into the said bottom are substantially parallel, the extensions of the narrow panels and of one said wider panel being of equal width or extent in the direction lengthwise of the panels, said width being substantially one half the width of a said wider panel, and the remaining flap extension being of greater width to provide an extension which in the folded bottom overlaps the opposite flap.

4. A receptacle having a rectangular body and an integral closed end, said receptacle consisting of the one-piece blank set forth in claim 1, folded to form the said receptacle and having the superposed portions of the folded blank adhered together by an adhesive material.

5. A receptacle having a rectangular body and

an integral closed end, said receptacle consisting of the one-piece blank set forth in claim 3, folded to form the said receptacle and having the superposed portions of the folded blank adhered together by an adhesive material.
